UNITED STATES PATENT OFFICE

BERTHOLD W. FRANKEL, OF BROOKLINE, MASSACHUSETTS

HAIR-DRESSING BOOTH

Application filed July 11, 1928. Serial No. 291,908.

This invention relates to hair-dressing booths and has for its object to provide a booth having various novel features which will hereinafter be described and then

5 pointed out in the appended claim.

In the drawings, Fig. 1 is a perspective view of one end of a hair-dressing booth embodying my invention showing the arrangement of the booth with the working apparatus concealed;

Fig. 2 is a similar view showing the booth in condition for washing or drying hair;

Fig. 3 is an enlarged section on the line 3—3, Fig. 1;

15 Fig. 4 is an enlarged detail view of the guide for the sliding mirror.

The ordinary hair-dressing booth is provided with a chair for the customer, a wash bowl which is usually placed against one wall and at which the hair may be washed, a hair drying apparatus for drying the hair, hair curlers and various other instruments. These are usually continually exposed to view so that when a customer enters the 25 booth all the working apparatus is visible.

One of the objects of my present invention is to provide an improved hair-dressing cabinet which is so arranged that all of the working apparatus may be concealed from view 30 behind panels, doors, etc., which are so arranged that when they are in their operative position they apparently form one of the side walls of the booth or compartment. These panels, doors, or other movable elements may be swung out of the way to give 35 access to the bowl, hair-drying device and other implements when the latter are needed.

Referring now to Fig. 2 of the drawings which illustrates in perspective view one end 40 or side of a hair-dressing booth, 1 indicates generally a wash-bowl of any approved type which is provided with hot and cold water faucets 2 and 3. The bowl is arranged with a cupboard or closet beneath it which may be 45 closed by a door or panel 4. Situated at one side of the bowl is a counter or table top 5 beneath which may be provided drawers 6 and a compartment closed by a suitable door 7. 50 8 indicates a hair-drying apparatus which is mounted on the counter 5 and is

preferably of the type which can be swung around into different angular positions so as to present the nozzle 9 into different positions for use.

10 indicates a heater for hair curling implements, and if desired the counter 5 may support other working apparatus and also forms a table on which scissors, nail-files and other implements may be placed.

The bowl 1 is shown as placed approximately centrally of the wall 11 of the booth and on the side of the bowl opposite to the counter 5 I have provided a closet 12 which is closed by a door 13. This closet is designed to receive the wraps of the customers and also of the attendant, if desired.

The closet is so built that the door 13 comes substantially flush with the panel 4.

14 indicates a wall plug to which electric connections can be attached for heating curling irons or any implements.

15 indicates a door or panel which is hinged to the wall and is adapted to shut against the counter 5 as shown in Fig. 1. When this door or panel is in closed relation it conceals the counter 5 and also the main portion of the hair-drying apparatus as well as any other implements or devices that may be on the counter.

16 indicates a mirror which is slidably mounted so that it can be moved from a position in front of the closet door 13 as shown in Fig. 2 to a position in front of the bowl as shown in Fig. 1. When this mirror is in the latter position it conceals the bowl and faucets from view and also the nozzle end of the hair-drying device.

The mirror is shown as having brackets 17 at its upper end carrying supporting rollers 18 and these rollers run on a track 19 which is formed in the heading 20 at the upper end of the booth. The track is concealed from view and it is located in a groove formed in the lower side of the heading and the hangers 17 are so arranged that the front face 21 of the mirror comes substantially flush with the face 22 of the heading.

The bottom of the mirror is guided and held in position by a guiding finger 26 carried by a bracket 27 that is secured to the wall,

said finger entering a groove 25 formed in the bottom edge of the mirror 16.

The track is arranged to permit the mirror to slide from its central position shown in Fig. 1 to a position shown in Fig. 2 in which it exposes the bowl and also stands in front of the closet door 13.

The transverse dimension of the mirror 16 is such that it substantially fills the space between the door 13 and the panel 15 when the latter is closed and hence when said panel is closed and the mirror is in its right hand position, as shown in Fig. 1, all of the working devices are entirely concealed from view and the end of the room presents the appearance of a mirror situated between two doors.

The booth will preferably be of such a size that the doors 13, 15 and the mirror extend from one side wall 23 of the booth to the other side wall 24 thereof. When a customer enters the booth, therefore, the working end thereof has the appearance shown in Fig. 1, that is, the appearance of the wall of a room formed of two doors with a mirror situated between them. When work on the customer commences the panel 15 may be opened or the mirror 16 may be moved into the position shown in Fig. 2 or both the panel and the mirror may be moved into their open position depending upon the character of the work which the customer requires and upon location of the implements with which to perform the work. When the work has been accomplished the panel 15 and/or the mirror 16 may be closed thus concealing again the working apparatus.

When the panel and mirror are in closed relation the booth presents the appearance of a room which has in it simply the operating chair and possibly one or two other chairs but does not present the appearance of a work shop, as would be the case if all the working apparatus were exposed to view.

I claim.

A hair-dressing booth having at one end a closet provided with a swinging door and a compartment adjacent said closet to receive working apparatus and a two-part closure for said compartment comprising a swinging door or panel and a sliding mirror, the door or panel being pivotally hung at the end of the compartment opposite the closet and when closed partially closing the compartment and the mirror being slidable toward and from the free edge of the door when the latter is closed and in a plane parallel thereto, said mirror being of a dimension to close the portion of the compartment between the free edge of the door or panel when the latter is closed and the closet, and being slidable in front of the closed closet door to open the compartment.

In testimony whereof, I have signed my name to this specification.

BERTHOLD W. FRANKEL.
